CLAIM

The ornamental design for a headlight for motor vehicle as shown and described.

DESCRIPTION

FIG. 1 is a perspective view of a headlight for motor vehicle according to a first embodiment showing my new design; FIG. 2 is a front view thereof; FIG. 3 is a right view thereof; and FIG. 4 is a top view thereof.

FIG. 5 is a perspective view of a headlight for motor vehicle according to a second embodiment showing my new design; FIG. 6 is a front view thereof; FIG. 7 is a left view thereof; and, FIG. 8 is a top view thereof.

The broken lines in the drawings illustrate portions of the headlight for motor vehicle which forms no part of the claimed design.
